UNITED STATES PATENT OFFICE.

EDWARD WILLIAM MACKENZIE-HUGHES, OF CHICAGO, ILLINOIS, ASSIGNOR
TO THE FOX SOLID PRESSED STEEL COMPANY, OF SAME PLACE.

LOCOMOTIVE FRONT PLATE.

SPECIFICATION forming part of Letters Patent No. 423,517, dated March 18, 1890.

Application filed March 12, 1889. Serial No. 303,017. (No model.)

To all whom it may concern:

Be it known that I, EDWARD WILLIAM MACKENZIE-HUGHES, of Chicago, Cook county, Illinois, have invented a new and useful Improvement in Locomotive Front Plates, of which the following is a full, true, and exact description, reference being had to the accompanying drawings.

This invention relates to an improved construction of locomotive front plate and number-plate combined, by which the door of the front plate is locked by the same bar which supports the front plate.

My invention will be readily understood from the accompanying drawings, in which—

Figure 1 represents an elevation of my front plate in position, and Fig. 2 a horizontal section through the same; Fig. 3, a view, partly in vertical section, showing the arrangement of the locking device.

The parts A, K, and H of this structure are all, by preference, made of pressed steel, pressed between dies to the forms indicated.

A represents the front plate itself. To this is hinged by hinge C the smoke-box door K. The number-plate is shown at H, supported upon the rod D, which has at its inner end the T-head for locking the door. Within the front plate A, which is preferably corrugated at B, is the cross-bar F, provided with an opening, through which the head E of the bolt D will pass in one position, but when turned will lock within the bar, as shown in the drawings.

G represents a nut of any suitable construction screwing upon the thread cut on the outer end of the bolt D. By loosening the

nut G and turning the number-plate at right angles the bolt D will draw through the bar F and the door K can be opened. By reversing the operation the door can be tightly closed against the front plate.

What I claim as my invention, and desire to secure by Letters Patent, is—

1. The combination of locomotive front plate and door herein shown, which consists of a front plate and door hinged thereto, a transverse bar within the front plate, a bolt carried by the door and having a head locking in one position within the cross-bar and in another position passing therethrough, and a nut outside the door for locking the same when closed, substantially as described.

2. The combination of a boiler front plate, a door hinged thereto, and a cross-bar within the same, a bolt carried in said door and passing through said cross-bar for locking the door, the said bolt likewise carrying a number-plate at its outside end, and a nut for locking the door in its closed position, substantially as described.

3. The combination of the front plate A, the door K, hinged thereto, the bar F, having longitudinal opening therethrough, and a bolt D, passing through the bar F and on its outer end carrying the number-plate H and nut G, substantially as described.

In testimony whereof I have signed my name to this specification in the presence of two subscribing witnesses.

EDWARD WILLIAM MACKENZIE-HUGHES.
